INVENTOR.

James A. Henry

BY *Chappell & Carl*

ATTORNEY.

UNITED STATES PATENT OFFICE.

JAMES A. HENRY, OF STURGIS, MICHIGAN, ASSIGNOR OF ONE-HALF TO THADDEUS S. WAIT, OF STURGIS, MICHIGAN.

CURTAIN FIXTURE.

Application filed February 23, 1922. Serial No. 538,616.

To all whom it may concern:

Be it known that I, JAMES A. HENRY, a citizen of the United States, residing at Sturgis, county of St. Joseph, State of Michigan, have invented certain new and useful Improvements in Curtain Fixtures, of which the following is a specification.

This invention relates to improvements in curtain fixtures.

10 The main objects of the invention are:

First, to provide an improved curtain fixture in which the rod may be quickly engaged with or disengaged from its supporting bracket and at the same time one which 15 is securely retained thereon.

Second, to provide an improved curtain rod and supporting bracket which does not necessitate the mounting of the bracket as rights or lefts.

20 Further objects, and objects relating to structural details, will definitely appear from the detailed description to follow.

I accomplish the objects of my invention by the devices and means described in the 25 following specification. The invention is clearly defined and pointed out in the claims.

A structure which is a preferred embodiment of my invention is clearly illustrated 30 in the accompanying drawing, forming a part of this application, in which:

Fig. I is a top view of a curtain fixture embodying the features of my invention, parts being broken away for convenience in 35 illustration.

Fig. II is a vertical section on a line corresponding to line 2—2 of Figs. I and III.

Fig. III is a vertical section on a line corresponding to line 3—3 of Fig. II.

40 Fig. IV is a detail view with the bracket and rod disengaged illustrating one position in assembling or disassembling.

Fig. V is a detail view illustrating another position of the parts in assembling or 45 disassembling.

In the drawing similar reference characters refer to similar parts throughout the several views, and the sectional views are taken looking in the direction of the little 50 arrows at the ends of the section lines.

Referring to the drawing, the curtain rod 1 is of the commercial flat rod type having inturned flanges 2 at its edges. I provide wall brackets 3 comprising wall plates per-

forated at 4 to receive the attaching brads 55 or screws and having flat projecting arms 5.

The lower edges 6 of these arms are straight or horizontal and the lower corners 7 are preferably rounded, as shown. The upper edges 8 are inclined inwardly providing a 60 cam projection 9 adjacent the outer end of the fixture. The width of the bracket arm preferably through this cam projection is

such that the rod cannot be slipped upon the arm when presented horizontally thereto 65 without somewhat springing or distorting the rod. However, by presenting the rod to

the bracket at the angle of the inclined edge of the bracket as shown in Fig. V the rod 70 may be engaged with a tilting sliding movement and when swung to the horizontal position as shown in Fig. III with the lower edge of the bracket lying within the channel a clutching action is secured at 9 and at the lower edge of the bracket, effectively 75 supporting the rod against a pull longitudinally of the bracket. However, the rod may be easily disengaged by swinging upwardly to the position shown in Fig. V and an outward pull thereon.

80 With this arrangement of parts the parts are held in engagement very securely and at the same time may be disengaged as occasion requires. The parts of my improved curtain fixture are very simple and economical to produce and strong and durable 85 and not likely to become distorted or inoperative in use or in assembling or disassembling.

Having thus described my invention, what 90 I claim as new and desire to secure by Letters Patent, is:

1. In a curtain rod fixture, the combination of a curtain rod member having inturned edges, and a bracket having a flat 95 arm with a horizontal bottom edge and an inwardly inclined upper edge providing a clutching cam at its outer end with which said curtain rod member may be engaged with a tilting movement, the lower corner 100 of said arm being rounded.

2. In a curtain rod fixture, the combination of a channeled curtain rod member, and a wall bracket having a flat arm with a horizontal bottom edge and an inwardly inclined upper edge providing a clutching cam with which said curtain rod member 105 may be engaged with a tilting movement.

3. In a curtain rod fixture, the combination of a curtain rod having inturned edges, and a flat bracket member having a cam projection on its upper edge permitting the engagement of the curtain rod member with the bracket by a tilting movement, the width of the bracket through its cam projection being such as to secure a clutching engagement with the rod when the rod member is 13 swung to a horizontal position with its lower edge in engagement with the under edge of the bracket arm.

4. In a curtain fixture, the combination of a curtain rod having opposed flanges, a wall 15 bracket having a flat arm with a horizontal bottom edge and a cam projection on its upper edge, said cam having an inwardly inclined edge, the lower corner of said arm being rounded, the width of the arm through 20 its cam being such as to provide a clutching engagement with the flanges when the

rod member is swung to operative position on the arm.

5. In a curtain rod fixture, the combination of a bracket having a projecting arm 25 with an upwardly extending cam projection adjacent its outer end, and a curtain rod adapted to be engaged over said arm with a downwardly swinging movement which brings the cam into frictional clutching engagement with said rod member. 30

6. In a curtain rod fixture, the combination of a curtain rod, and a bracket member having an arm adapted to extend into said rod, said arm having a cam projection permitting the engagement of the rod with the bracket by tilting movement, the parts having a clutching engagement when the rod is 35 swung to its operative position.

In witness whereof, I have hereunto set 40 my hand and seal.

JAMES A. HENRY. [L.S.]
